UNITED STATES PATENT OFFICE.

EBENEZER POMEROY, OF LITHONIA, GEORGIA.

FIREPLACE.

1,193,054.

Specification of Letters Patent.

Patented Aug. 1, 1916.

Application filed April 5, 1913. Serial No. 759,121.

To all whom it may concern:

Be it known that I, EBENEZER POMEROY, a citizen of the United States, residing at Lithonia, in the county of Dekalb and State 5 of Georgia, have invented certain new and useful Improvements in Fireplaces, of which the following is a specification.

This invention relates to improvements in fire-places, and has primarily for its object 10 the provision of a simple, neat and attractive fire-place wherein the several embodiments are arranged and constructed in such a novel and peculiar manner as to be capable of ready and quick detachment should 15 occasion demand.

A further object of the invention resides 20 in the provision of a specially devised outer casing wherein means is provided for supporting the fire-box, fender and other embodiments employed in connection therewith, the arrangement of the draft openings of the said casing being so disposed as to render combustion extremely favorable.

The above and additional objects are 25 accomplished by such means as are illustrated in their preferred embodiment in the accompanying drawings, described in the following specification and then more particularly pointed out in the claims which are appended 30 hereto and form a part of this application.

In describing my invention in detail reference will be had to the accompanying drawings wherein like characters denote like or corresponding parts throughout the 35 several views, and in which:—

Figure 1 is a front elevation of a fireplace constructed in accordance with my invention; Fig. 2 is a section on line 2—2 of Fig. 1; Fig. 3 is a detail perspective view of 40 the fire-box; Fig. 4 is a plan view of the grate; Fig. 5 is a detail perspective view of the grate supporting means; Fig. 6 is a similar view of the casing top; and Fig. 7 is a detail perspective view of a modified form 45 of fire-box.

Referring now more particularly to the drawings, wherein is illustrated the preferred form of my invention the numeral 1 designates a rectangular face plate adapted 50 to surround the openings in a fire place, on which plate or frame is mounted a box like structure adapted to project from said frame into a room. The said structure comprises a pair of vertical side metal strips 55 connected at the top by a cross piece, the said uprights or sides having two parallel vertically extending spaced apart side walls

2 secured in any suitable manner thereto, which walls terminate at their upper extremity in an angular top piece 3 having 60 side flanges 4, and a horizontally extending flange 5, formed integrally therewith, the said flanges rigidly connecting the said top piece to the side walls 2 by means of the said side flanges 4, and said top being connected to the face plate 1, by means of the longitudinally extending flange 5. The provision of the angular or slanting top 3 adds materially to the efficiency of the fire-place and prevents the passage of smoke into the 70 room or hall within which the fire-place is built.

A fire-box, designated in its entirety by the numeral 6 is disposed between the lower portion of the casing sides 2, such fire-box preferably comprising an angular rear wall 7 and side walls 8 the latter having formed integrally therewith ears or projections 9, the purpose of which will subsequently appear. The upper extremity of 80 the inclined rear wall 7 of the fire-box is provided with a laterally extending flange 10, the edge of the said flange, in actual practice, being adapted to fit against the rear wall of the wall of the room in which 85 the fireplace is located to prevent the accumulation of soot and other foreign matter behind the said fire-box. Another flange 11 is formed at the base of the said fire-box 6 and extends inwardly therefrom as is 90 clearly shown in Fig. 3, the provision of which creates a support for a suitable grate 12 connected thereto, the latter being secured upon the upper face of the flange 11 through the medium of bolts 13. A base 95 plate or support member 14, shaped to conform to the configuration of the flange 11 of the fire-box is arranged between the said fire-box and the floor upon which the fireplace is built, the said member 14 having an 100 inwardly directed flange 15 formed integrally therewith and at the top thereof upon which the flange 11 of the fire-box normally rests where it is held securely by means of the fastening means designated by the number 13.

A fender 16 of any construction may be secured to the front of the fire-box through the medium of the ears 9 formed thereupon, the said fender in its preferred form comprising a plurality of uniformly spaced apart horizontally extending bars, the upper of which is disposed upon the same plane as the flange 10 of the fire-box.

Openings 17 are formed within the casing sides for effecting a draft to the fire-box from the sides thereof while the provision of the supporting member 14 will deflect the draft at the base of the grate upwardly and into the fire-box thereby producing the desired combustion necessary in devices or apparatus of this character.

Referring now to the modification shown in Fig. 7, the fire-box shown therein is provided with angularly disposed rear walls 18 converging from the sides of the said fire-box, the flange 19 thereof being likewise converged to conform to the shape of the said rear walls 18 of the box. When the fire-box is constructed as above described, the base or supporting member should be slightly modified, the construction being determined by the shape of the rear wall 18 of the said box, thereby providing for engaging flanges as in the preferred form.

It will be seen from the above, taken in connection with the accompanying drawings that the provision of the angularly disposed casing top 3 will deflect and guide all smoke issuing from the fire up through the chimney as desired; that the fire-box is elevated sufficiently above the floor to insure perfect combustion; and that the provision of the base or supporting member in conjunction with the angular face of the said fire-box will at all times create the desired draft necessary in fire places constructed in a manner similar to that above described.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. A sectional fire-place including a supporting structure, side walls secured thereto, an inclined top connecting the said side walls, a flanged support member arranged between said side walls at the base thereof, a flanged fire-box mounted upon said support member, the flanges of said support and said box being shaped to conform one with the other, a fender carried by said fire-box, and a flange projecting rearwardly from said fire-box, said flange being disposed for engagement with the rear wall of a room, as and for the purpose set forth.

2. A sectional fire-place including a supporting structure, side walls secured thereto, the said walls having openings formed therein, a top piece connecting the said side walls, a support member arranged between the said side walls at the base thereof, an inwardly directed flange formed at the top of the said support, a fire-box mounted upon the said support, an inwardly directed flange formed at the base of the said fire-box and disposed for engagement with the said support flange, a grate arranged within the said fire-box and supported by the said flanges, a fender carried by the said fire-box, and a flange projecting rearwardly from the said fire-box at the top thereof, said flange being disposed for engagement with the rear wall of a room, as and for the purpose set forth.

3. A sectional fire-place including a supporting structure, side walls secured thereto, the said walls having openings formed therein at a point intermediate the ends thereof, an inclined top connecting said side walls, the said top having end flanges and a longitudinally extending flange formed integrally therewith, the said end flanges being disposed for engagement with the said side walls, the said longitudinal flange being disposed for engagement with the said supporting structure, a substantially rectangular support member arranged between the said side walls at the base thereof, an integrally formed inwardly directed flange projecting from the top of the said support member, a fire-box, the base of which is provided with an integrally formed inwardly directed flange shaped to conform with the said support flange, the rear wall of the said fire-box being disposed upon an incline, an integrally formed flange at the top of the said fire-box, the said flange being disposed for engagement with the wall of the room, the said rear wall of the fire-box and the said support member being disposed in spaced relation to the said supporting structure, the openings in the sides of the fire-place having communication with the space behind the said fire-box and the said support, a grate member arranged within the said fire-box and supported by the flange of the fire box, a fender carried by the said fire-box, and tongues formed integrally with the said fire-box and disposed to overlap the said fender to provide a securing means therefor, as and for the purpose set forth.

In testimony whereof I affix my signature in presence of two witnesses.

EBENEZER POMEROY.
